UNITED STATES PATENT OFFICE

REUBEN FRANCIS O'NEIL, OF OAKLAND, CALIFORNIA

FILING APPARATUS

Application filed February 27, 1929. Serial No. 343,119.

- This invention relates to the filing of bills and other small papers such as are handled over the counters of grocery stores, restaurants, drug-stores and the like, and particularly relates to an apparatus for use when it is desired or necessary to permanently, or at least for a considerable length of time, keep the bills, etc. stored away for future reference.
- 10 The principal object of the present invention is to provide an apparatus especially intended for the initial filing and subsequent storing of drug-store prescriptions, which apparatus includes an initial bill file and a subsequent storing file, so related to each other that when the initial bill file is full the stack of papers thereon is removed as a unit and applied to the storage file without disturbing said stack.
- 20 In this manner a single initial filing device is all that is necessary for any one store, while any desired number of storage files, to cooperate with said single file and of relative simpler and less expensive nature, may be provided for use as the occasion arises.

A further object of the invention is to produce a simple and inexpensive device and yet one which will be exceedingly effective for the purpose for which it is designed.

- 30 These objects I accomplish by means of such structure and relative arrangement of parts as will fully appear by a perusal of the following specification and claims.

In the drawings similar characters of reference indicate corresponding parts in the several views:

Fig. 1 is a side elevation of the initial bill filing device, partly in section to show the detachable mounting of the spike.

- 40 Fig. 2 is a view of the spike and a stack of papers detached.

Fig. 3 is a fragmentary view of a spike and stack as applied to a storage file.

- 45 Fig. 4 is a fragmentary perspective view showing a storage filing arrangement.

Referring now more particularly to the characters of reference on the drawings, the initial file unit is substantially the same construction as is shown in my Patent No. 1,705,306, dated March 12th, 1929. This de-

vice includes a portable hollow base 1 from one side of which a substantially vertical rod 2 projects upwardly.

This rod terminates at its upper end in a horizontal portion 2^a overhanging the base 55 and at the outer end of which a downwardly depending vertically adjustable guard cap 3 is mounted. The rod 2 may be swung to one side from a normal position by an actuating lever 4 projecting upwardly through the base 60 and operatively connected to the rod in the same manner and as fully disclosed in the above mentioned patent and for the same purpose.

The bill impaling spike 5 projects upwardly from the base in vertical alinement with the guard cap when the rod 2 and cap are in their normal positions. This spike is threaded certain distances from both ends and toward its lower end is adapted to pass 70 freely through a boss 6 formed on the base 1. A permanently mounted nut or collar 7 is fixed on the spike above the boss and a removable nut 8 is normally threaded on the spike below the collar 7, with a removable 75 washer 9 normally disposed between the members 7 and 8.

When the spike is mounted in connection with the base the nut 8 is screwed up as close to the collar 7 as possible and its under side 80 then bears against the boss; the lower end of the spike then projecting some distance into the open space of the hollow base below the supporting boss. A removable sleeve nut 10 is then screwed onto the lower end of the 85 spike and into clamping engagement with the under side of the boss to hold the spike in a rigid immovable position.

The file is then in condition to receive the prescription leaflets 11 or other papers which are impaled on the spike as received. In order to provide a gage for impaling the individual leaflets at a predetermined point in the length of the same, the rod 2 is bent to extend somewhat close and parallel to the 95 spike for a short distance both above and below the point of said spike as shown.

This portion of the rod therefore forms a stop for the edge of each leaflet when the latter is inserted between the guard cap and the 100

point of the spike prior to being impaled. At the same time the pivotal connection of the rod with the base is removed a sufficient distance away from the spike so that when 5 the rod is swung to one side the upper portion and the guard cap will be clear of the spike a considerable distance.

When the spike has been filled with the leaflets to a certain extent and it is desired 10 to store the accumulated prescription leaflets, the base is raised, and the nut 10 is removed and temporarily applied to the upper end of the spike so as to keep the leaflets from coming off the spike while being taken to the stor- 15 age cabinet C.

The cabinet is preferably divided into a number of compartments as shown in Fig. 4, each adapted to receive a supporting plate or tray 12 for each stack of leaflets. The 20 plate 12 is raised from the floor of its compartment a sufficient distance to freely receive the height of the nut 10 thereunder by end flanges or feet 13 on the plate, the rearmost of which engages a rotating lip 14 extending 25 across the bottom of the floor at the back. The front flange has an opening to removably receive a spring catch member 15 of suitable character mounted on and projecting upwardly from the floor and acting in connection with the lip to detachably retain the tray against displacement. An opening 16 is preferably cut in the floor of each compartment near the front so as to enable the tray to be engaged by the fingers of the 30 operator from below and pushed up so as to disengage the same from the clip. A holder 17 for a card to bear the necessary identifying data of the stack of leaflets supported by the tray is mounted on the front of the tray 35 above the holding clip.

When the leaflet and spike unit are brought to the tray the latter is first removed from the cabinet and the nut 8 and the washer 9 are then removed from the lower end of the spike, the latter being inverted to facilitate 40 this operation and the nut 10 preventing the leaflets dropping off. The spike is again upended, and the nut 10 is removed and is replaced by the washer and nut 7, which is 45 turned down firmly to bind the stack of leaflets together as a compact unit, the washer being of course applied first and preventing the nut from cutting into and tearing the top-most leaf as said nut is turned. The nut 7 50 remains undisturbed and practically forms a permanent stop or shoulder for the bottom of the stack. This operation completed, the lower end of the spike is inserted through an 55 opening provided in the tray at the proper point and the nut 10 is reapplied to the spike below the tray to secure the two together in rigid relationship. The tray is then replaced in its compartment in the cabinet and the spike of an adjacent tray, which is to be 60 used for the next stack of leaflets, is removed.

from its tray together with the complement of nuts and is then applied to the original file base 1 in the manner previously set forth. The initial filing device is then ready to receive another stack of leaflets as they are received.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A bill file including a base member, a vertical spike extending upwardly from the base, said spike being threaded to the same size and pitch on both ends, a permanent stop above the lower end of the spike, said spike projecting freely down through the base and the stop limiting the extent of such projection, and a nut adapted to screw onto the lower end of the spike to clamp the stop against the base or to be applied to the top of the spike to hold a stack of leaflets thereon against displacement when the spike is detached from the base.

2. A bill file including a base member, a vertical spike extending upwardly from the base, said spike being threaded to the same size and pitch on both ends, a permanent stop above the lower end of the spike, said spike projecting downwardly through the base and the stop limiting the extent of such projection, a nut adapted to normally screw onto the lower end of the spike to secure the same in detachable connection with the base, and an additional nut to removably screw onto the upper end of the spike normally mounted thereon immediately under the stop.

3. A bill file including a base member, a vertical spike projecting upwardly therefrom, a rod mounted at its lower end on the base for turning movement about a vertical axis; said rod above its lower end being bent to extend parallel and normally relatively close to the spike for a distance above and below the point of the same whereby serve as a gage for papers when being impaled on the spike.

In testimony whereof I affix my signature.

REUBEN FRANCIS O'NEIL.
